DESIGN FOR A SEWING RACK

Maude M. Atherton, Orange, Tex.

Application March 23, 1945, Serial No. 118,653

Term of patent 14 years

(Cl. D3—19)

To all whom it may concern:

Be it known that I, Maude M. Atherton, a citizen of the United States, residing at Orange, in the county of Orange and State of Texas, have invented a new, original, and ornamental Design for a Sewing Rack, of which the following is a specification, reference being had to the accompanying drawing, forming a part thereof.

The figure is a front perspective view of a sewing rack, showing my new design.

The rear or back of the sewing rack is plain and unornamented.

I claim:

The ornamental design for a sewing rack, as shown and described.

MAUDE M. ATHERTON.
